MEANS FOR CONTROLLING PATTERNING
AND OTHER OPERATIONS OF KNITTING
MACHINES

Alfred Woodward Kent and Henry Harold Holmes, Leicester, England, assignors to Wildt and Company Limited, Leicester, England, a British company

Application April 12, 1939, Serial No. 267,488
In Great Britain April 28, 1938

18 Claims. (Cl. 66—154)

This invention relates to means for controlling patterning and other operations or movements of knitting machines and concerns in particular patterning or other controlling mechanism including a device or unit having patterning or other controlling formations thereon and adapted to operate with step-by-step movement such, for example, as may be imparted by pawl and ratchet mechanism for purposes with which those familiar with the art are well acquainted.

Such a device or unit may consist of a wheel drum or like body with pins, pegs, cam bits, jacks, pressers or like elements prearranged therein or thereon to provide a desired patterning or controlling formation, or a wheel drum or like body adapted to carry a chain provided with various links or bits prearranged, or a jacquard band perforated in a prearranged manner to provide a required patterning or controlling formation.

Mechanisms of this kind are in common use on knitting machines, and especially circular knitting machines for selectively operating instrumentalities such as needles, jacks, sliders, thread guides for lap or wrap striping effects (embroidery plating) reverse plating sinkers or like elements for patterning or designing purposes, and it is sometimes desirable to utilize the same patterning or controlling device or unit to produce different results, such for example as selective operation of the needles, jacks, sliders, thread, lapping or wrapping guides, sinkers or like instrumentalities as aforesaid, and the shogging of one set or series of instrumentalities in relation to another or a co-operating set or series of instrumentalities. For instance, with regard to lap or wrap striping it is sometimes desirable to shog the series of thread guides in relation to the needles to produce shogged effects as well as selectively to operate the thread guides, according to patterning requirements.

The present invention has for its object to improve patterning or controlling mechanism of the kind aforesaid in certain respects as will be hereinafter set forth.

In the accompanying drawings:

Figure 1 is a plan view of a specific form of pattern device or unit and associated parts constituting an example of the invention.

Figure 2 is a vertical sectional view taken on the line II—II of Figure 1.

Figure 3 is a front elevational view of the device or unit, i. e., as seen in the direction of the arrow A in Figure 1.

Figure 4 is a detail sectional plan view, taken on the line IV—IV of Figure 2, showing spring means

through the medium of which one part of the device or unit is operated.

Figures 5 and 6 are two further sectional plan views, taken on the lines V—V and VI—VI of Figure 2 respectively, and illustrating more clearly the forward and reverse actuating mechanism employed for operating the device or unit.

Like parts are designated by similar reference characters throughout the drawings.

Referring to the drawings—and more particularly to Figure 2—it will be seen that the pattern device or unit comprises two drums or like parts 1 and 2, one fixedly and the other freely mounted co-axially on a suitable spindle, conveniently a hollow spindle such as 3 for mounting rotatably on an axle or shaft 4 fixed in a bracket 5 or a like support. As shown in Figure 2 the fixedly mounted drum or like part 1 is formed with a central hub or boss 6 which is keyed to the spindle 3 as indicated at 7. The freely mounted drum or like part 2 is formed with a neck 8 having a radial lug 9 (or a like projection) thereon at one end. The hollow spindle 3 has keyed thereon juxtaposed co-axial ratchet wheels 10 and 11 of the positive type, said wheels having teeth 12 of the same pitch and being oppositely arranged so as to enable forward and reverse rotation to be imparted to the spindle according to requirements as will be hereinafter more fully described. The ratchet wheel 10 is located adjacent to the neck 8 of the freely mounted drum or like part 2, and is connected therewith by an arrangement comprising a pair of arcuate blocks 13 (see Figure 4) located in a concentric groove 14 in the wheel, one on each side of the lug 9, a tension spring 15 engaged with a pair of screws 16 (or with pins or hooks) one in each block 13 at the end 13a opposing the lug 9, a pair of screws 17 one inserted in each block at the other end 13b, and a pair of plates 18 attached, e. g., by means of screws 19 to the ratchet wheel 10—one opposing the screw 17 in one block and the other opposing the corresponding screw in the other block. The blocks 13 are, as shown in Figure 4, furnished with split lugs or clips such as 20 for the reception of the screws 17 and other screws 21 are provided in said lugs or clips for fixing the screws 17 after adjustment. As will be understood the plates 18 retain the blocks 13 within the groove 14 and also serve another purpose hereinafter to be mentioned.

The freely mounted drum or like part 2 has a toothed disc or ring 22 attached to it at the end remote from the ratchet wheels 10 and 11 and a catch or detent 23 (see Figure 3) is slidably

- mounted on, or as shown in, the bracket 5, said catch or detent being urged into engagement with the toothed disc or ring 22 so as normally to prevent rotation of the drum or like part 2.
- 5 The catch or detent 23 is operated by a cam to release the drum or like part 2 in timed relation with the operative strokes of the pawl and ratchet mechanism. In the specific example illustrated the top of the drum or like part 2 is recessed peripherally for reception of the disc or ring 22 and the latter is conveniently secured to said drum or like part by means of screws 24. As will be seen in Figures 1 and 3 the catch or detent 23 is formed on a depending portion 15 25 of a small carrier plate 26 which latter is secured, as by means of a screw such as 27, to the forward end of a bar 28. This bar is slideable longitudinally in an appropriately recessed part of the bracket 5 and projects rearwardly of the 20 latter into the path of a cam 29 which, in the case of a circular knitting machine, revolves with or at the same speed as the cylinder or cylinders or with the cam box or cam boxes, as the case may be, so that the catch or detent is operated 25 at every revolution of said rotary parts. The bar is controlled by a tension spring 30 one end of which is connected to a peg or screw 31 in the bracket whilst the other end is anchored to a hook 32 secured in the bar. The carrier plate 30 26 is formed with an open-ended slot 33 for reception of a guide pin 34 fixed in the bracket, this pin serving to steady the plate. Normally therefore, the spring 30 urges the catch or detent 23 into engagement with the toothed disc or 35 ring 22 thereby preventing rotation of the drum or like part 2. However, at such times as the cam 29 acts upon the rear end of the bar 28 (in timed relation with the operation of the pawl and ratchet mechanism) said bar is pushed forward 40 against the spring action with the result that the catch or detent 23 is withdrawn from the teeth of the disc or ring 22 and the drum or like part 2 is released.
- The arrangement so far described is such that 45 normally the spring 15 pulls the blocks 13 up against the lug 9. When the ratchet wheels 10 and 11 are racked either clockwise or anti-clockwise the drum or like part 1 is racked to a corresponding extent and the spring 15 is tensioned so long as the freely mounted drum or like part 2 is held by the catch or detent 23. Consequently when said catch or detent is operated to release this drum or like part the latter is racked by the spring 15. The two drums or 50 like parts 1 and 2 are therefore racked one after the other. Conveniently in the application of this example of the invention to operation of knitting machine instrumentalities for patterning purposes the catch or detent 23 is operated 55 so that the freely mounted drum or like part 2 is racked one step in the desired direction after each step in the racking movement of the other drum or like part 1. In such application the freely mounted drum or like part may be utilized 60 for selective operation of said instrumentalities while the other drum or like part is employed to effect the shogging of one set or series of instrumentalities relatively to another set or series of instrumentalities. For these purposes both of 65 the said drums or like parts are adapted to receive pins, pegs, screws, presser elements or cam bits, and in this respect may be similar to each other apart from the prearrangement of such elements necessary to produce the desired different results, the drum or like parts may, as shown, 70 75

be of the same size diametrically, and of the same length or of different lengths. In the specific example illustrated each drum or like part is formed with series of small holes 35 each adapted for reception of a peg 36. The drums or 5 like parts are covered by a cylindrical casing 37 which has formed therein an opening or openings through which extend a bank of pivoted cam levers 38 of conventional form adapted to be operated selectively by the drum 2 and in turn 10 to effect selective operation of the appropriate instrumentalities. These cam levers may, if desired be spring controlled but in any event they are mounted to turn about a pivot 39 carried by the bracket 5 (see Figure 1). With regard to 15 the pegs 36 in the drum or like part 1 these are provided, in this particular example, for action, as shown in Figures 1, 2 and 3 on a toe piece 40 of a suitably spring controlled lever 41 which latter is pivoted at 42 on a side of the bracket 5 and 20 adapted when appropriately operated to effect, through intermediate mechanism of any conventional character, the shogging of one set or series of instrumentalities relatively to another set or series of instrumentalities. The lever 41 25 is controlled by a tension spring 43.

The invention may be applied to a patterning or controlling device or unit adapted to work on a vertical, horizontal or an obliquely disposed axis. 30

Preferably the operation of the respective parts or sections of the improved patterning or controlling mechanism is such that the changes thereby produced occur at the same needle or are restricted to only a few of the needles so 35 that the resultant effects in the knitting fabric are located on the same longitudinal line or thereabouts.

The invention, and especially the typical example herein described, is advantageously applicable to a patterning or controlling device or unit fitted with forward and reverse racking mechanism as and for the purpose set forth in the specification of British Letters Patent No. 443,736. Thus as will be seen more particularly 45 in Figures 3 and 5, the racking mechanism includes two clawers 44 and 45 for driving the ratchet wheels 10 and 11 respectively, these clawers being mounted on a reciprocatory bar 46 which is slideable through the bracket 5 and 50 slotted at 47 to accommodate the axle or shaft 4. Screw and nut means 48 are provided to set the clawers in the required positions on the bar 46 and the latter is formed with open-ended slots 49 to permit of adjustment of said clawers. A 55 lever 50 may conveniently be pivoted to the bar 46 at 51 and adapted to be operated, for reciprocating the bar, from timing or controlling mechanism on the machine; alternatively, the bar may be reciprocated directly from cam 60 means revolving with or at the same speed as the aforesaid rotary parts. The bar 46 is controlled by a suitably arranged compression spring 52 (see Figure 5) and the clawers are connected 65 together by a tension spring 53. A bluff member 54, formed with arcuate bluff portions 55, is mounted between the ratchet wheels 10 and 11 and arranged for turning movement about the axis of the axle or shaft 4. This member is movable angularly under the control of suitable 70 mechanism to release one or other of the clawers for engagement with the corresponding ratchet wheel or to render both clawers inoperative, all as described in the prior specification aforesaid. In the specific example illustrated 75

the bluff member is adapted to be operated by a bell crank 56 which is pivoted on the bracket 5 and connected to any operating rod 57.

For racking the device manually when required there may, as shown more clearly in Figure 6, be provided a handle 58 which is also suitably mounted to turn about the axis of the axle or shaft and is formed with an arm 59 which carries a spring-controlled pawl 60 adapted for engagement with the ratchet wheel 11.

Moreover, the example herein described may advantageously be employed in connection with the operation of the thread guides in the thread lapping or wrapping mechanism in a machine 15 of the double axially opposed needle cylinder type as described and claimed in the specification of British Letters Patent No. 455,801, the freely mounted drum or like part 2 being adapted for selective operation of the thread guides and 20 the other drum or like part 1 being adapted to effect shogging movement of the thread guides in relation to the needles to be lapped or wrapped.

As shown in Figures 1 and 3 the bracket 5 is formed with lugs 61 formed with bearings for reception of a post (not shown) fixed on the machine, said bracket being supported on this post in any suitable manner and arranged for swinging bodily movement on the latter so as to 30 enable the pattern device or unit as a whole to be readily moved into or away from its operative position. In this connection means of any convenient character may, if desired, be provided to render the pattern device or unit operative 35 and inoperative automatically as and when required. In any event a spring-controlled bolt member is preferably provided to maintain the bracket 5 in its position of use, said member being manually operable at will to release the bracket and enable it to be swung clear of adjacent parts of the machine as and when required. Such a bolt member is indicated at 62 in Figures 1 and 3 and, as will be seen, is recessed at 63 for engagement with a suitably positioned fixed part of the machine. The bolt member, moreover, is provided on a bar 64 which is slidable in the bracket and controlled by a tension spring 65. A retaining plate 66 serves to prevent the bar 64 from coming adrift from the bracket. The arrangement is therefore such that the bolt member, which is conveniently furnished with a knob 67 or the like, can be withdrawn against spring action from engagement with the aforesaid fixed part, and vice versa.

Means of a frictional character may be provided in conjunction with the drum or like part 1 to prevent this from over-running when racked round by the racking mechanism. Conveniently for this purpose, and as shown in Figure 2, a spring-pressed disc 68 is adapted to act frictionally upon the bottom of the drum 1. This disc is mounted on the hub 6 and held down by an intermediate member 69 which is in turn acted upon by compression springs such as 70. Adjustment of these springs can be effected by appropriate manipulation of the nuts 71 and the lower ends of said springs project through openings 72 provided in a part 73 which is prevented from rotation by a stud 74 passed into 70 it through the bracket 5.

As regards circular knitting machines the invention is applicable to patterning or controlling mechanism adapted for use in machines of the stationary as well as the rotary needle cylinder type, and in plain (non-rib) machines as well as

in machines of the cylinder and dial type and of the double axially opposed needle cylinder type for producing fabric in the piece, or knitted articles such as body garments or parts thereof, or seamless hose, half-hose and like articles, 5 separately or in string formation.

What we claim then is:

1. Controlling mechanism for a knitting machine comprising, in combination, a part presenting a controlling formation, actuating means for operating said part positively, another part presenting a controlling formation, spring means associated with the second mentioned part and adapted to be loaded by said actuating means and, when required, to impart movement to said second mentioned part, and means for releasably holding the latter from movement until the spring means are loaded, whereby upon release of said second mentioned part the spring means function to impart movement thereto. 20

2. Controlling mechanism for a knitting machine comprising, in combination, a part presenting a controlling formation, pawl and ratchet mechanism for operating said part positively, another part presenting a controlling formation, spring means associated with the second mentioned part and adapted to be loaded by said pawl and ratchet mechanism and, when required, to impart movement to said second mentioned part, and means for releasably holding the latter from movement until the spring means are loaded, whereby upon release of said second mentioned part the spring means function to 25 impart movement thereto. 30

3. Controlling mechanism for a knitting machine comprising, in combination, a part presenting a controlling formation, actuating means for operating said part positively, another part presenting a controlling formation, a tension spring arranged between said actuating mechanism and the second mentioned part, said spring being adapted to be tensioned by the actuating mechanism, and means for releasably holding said second mentioned part from movement until the tension spring has been tensioned, whereby 45 upon release of said part the spring functions to impart movement to the latter. 35

4. Controlling mechanism for a knitting machine comprising, in combination, a part presenting a controlling formation, actuating means adapted to transmit movement to said part positively first in one direction and then in the opposite direction for desired periods respectively, another part presenting a controlling formation, spring means associated with the second mentioned part and adapted to be loaded by said actuating means and, when required, to impart movement to said second mentioned part, and means for releasably holding the latter from movement until the spring means are loaded, 50 whereby upon release of said second mentioned part the spring means function to impart movement thereto. 55

5. Controlling mechanism for a knitting machine comprising, in combination, a part presenting a controlling formation, actuating means adapted to transmit movement to said part positively first in one direction and then in the opposite direction for desired periods respectively, another part presenting a controlling formation, 65 a tension spring arranged between said actuating mechanism and the second mentioned part, said spring being adapted to be tensioned by the actuating mechanism, and means for releasably holding said second mentioned part from movement 70

- until the tension spring has been tensioned, whereby upon release of said part the spring functions to impart movement to the latter whether said movement be a forward or a reverse movement.
6. Controlling mechanism for a knitting machine comprising, in combination, a part presenting a controlling formation, actuating means for operating said part positively, another part presenting a controlling formation, spring means associated with the second mentioned part and adapted to be loaded by said actuating means and, when required, to impart movement to said second mentioned part, a member which is applied to the spring operated part and furnished with teeth, a catch for co-operation with said teeth to hold said spring operated part from movement whenever the spring means are being loaded by the actuating means, and means for moving the catch out of engagement with the toothed member to release the spring operated part at predetermined times whereupon the spring means function to impart movement to said spring operated part.
7. Controlling mechanism for a knitting machine comprising, in combination, a bracket, a spindle rotatable in said bracket, a drum which presents a controlling formation and is fixedly mounted on said spindle, actuating means for rotating said drum positively step-by-step, another drum which presents a controlling formation and is freely mounted on said spindle, spring means which are associated with the freely mounted drum and adapted to be loaded by the actuating means, and means for releasably holding the freely mounted drum from movement until the spring means are loaded, whereby upon release of said freely mounted drum the spring means function to impart movement thereto.
8. Controlling mechanism for a knitting machine comprising, in combination, a bracket, a spindle rotatable in said bracket, a drum which presents a controlling formation and is fixedly mounted on said spindle, actuating means adapted to transmit turning movement to said drum positively first in one direction and then in the opposite direction for desired periods respectively, another drum which presents a controlling formation and is freely mounted on said spindle, spring means which are associated with the freely mounted drum and adapted to be loaded by the actuating means, and means for releasably holding the freely mounted drum from movement until the spring means are loaded, whereby upon release of said freely mounted drum the spring means function to impart movement thereto.
9. Controlling mechanism for a knitting machine comprising, in combination, a bracket, a spindle rotatable in said bracket, a drum which presents a controlling formation and is fixedly mounted on said spindle, actuating means for rotating said drum positively step-by-step, another drum which presents a controlling formation and is freely mounted on said spindle, a tension spring arranged between said actuating means and the freely mounted drum, said spring being adapted to be tensioned by the actuating means, and means for releasably holding said freely mounted drum from movement until the tension spring has been tensioned, whereby upon release of said last mentioned drum the spring functions to impart movement to the latter.
10. Controlling mechanism for a knitting machine, comprising, in combination, a bracket, a spindle rotatable in said bracket, a drum which presents a controlling formation and is fixedly mounted on said spindle, two juxtaposed coaxial ratchet wheels which are keyed on the spindle, said wheels having teeth of the same pitch and being oppositely arranged, actuating means adapted for co-operation with said teeth so as to impart forward and reverse rotation to the spindle according to requirements, another drum which presents a controlling formation and is freely mounted on said spindle, spring means which are associated with the freely mounted drum and adapted to be loaded by the actuating means, and means for releasably holding the freely mounted drum from movement until the spring means are loaded, whereby upon release of said freely mounted drum the spring means function to impart movement thereto.
11. Controlling mechanism for a knitting machine comprising, in combination, a bracket, a spindle rotatable in said bracket, a drum which presents a controlling formation and is fixedly mounted on said spindle, two juxtaposed coaxial ratchet wheels which are keyed on the spindle, said wheels having teeth of the same pitch and being oppositely arranged, a pair of spring-controlled clawers one for co-operation with each ratchet wheel, a bar upon which said clawers are mounted, means for reciprocating said bar to impart operative and idle strokes to the clawers, a movable bluff member formed with arcuate bluffing portions for controlling engagement of the clawers with the ratchet wheels, said wheels, clawers and associated parts together constituting means for enabling forward and reverse rotation to be imparted to the spindle according to requirements, another drum which presents a controlling formation and is freely mounted on said spindle, spring means which are associated with the freely mounted drum and adapted to be loaded by the actuating means, and means for releasably holding the freely mounted drum from movement until the spring means are loaded, whereby upon release of said freely mounted drum the spring means function to impart movement thereto.
12. Controlling mechanism for a knitting machine comprising, in combination, a bracket, a spindle rotatable in said bracket, a drum which presents a controlling formation and is fixedly mounted on said spindle, two juxtaposed coaxial ratchet wheels which are keyed on the spindle, said wheels having teeth of the same pitch and being oppositely arranged, a pair of spring-controlled clawers one for co-operation with each ratchet wheel, a bar upon which said clawers are mounted, means for reciprocating said bar to impart operative and idle strokes to the clawers, a movable bluff member formed with arcuate bluffing portions for controlling engagement of the clawers with the ratchet wheels, said wheels, clawers and associated parts together constituting means for enabling forward and reverse rotation to be imparted to the spindle according to requirements, another drum which presents a controlling formation and is freely mounted on the aforesaid spindle, a tension spring arranged between said actuating means and the freely mounted drum, said spring being adapted to be tensioned by the actuating means, and means for releasably holding said freely mounted drum from movement until the tension spring has been tensioned, whereby upon release of said last mentioned drum the spring functions to impart movement to the latter.
13. Controlling mechanism for a knitting ma-

chine comprising, in combination, a bracket, a spindle rotatable in said bracket, a drum which presents a controlling formation and is fixedly mounted on said spindle, two juxtaposed coaxial ratchet wheels which are keyed on the spindle, said wheels having teeth of the same pitch and being oppositely arranged, actuating means adapted for co-operation with said teeth so as to impart forward and reverse rotation to the spindle according to requirements, another controlling drum which has formed thereon a radial lug and is freely mounted on said spindle, a pair of blocks mounted for movement slidably in one of the ratchet wheels, one on each side of said lug, a pair of pins one in each block at the end thereof opposing the lug, a tension spring which is engaged with said pins, a pair of screws one inserted in each block at the other end, a pair of plates attached to the last mentioned ratchet wheel, one plate opposing the screw in one block and the other plate opposing the screw in the other block, the arrangement being such that the spring is tensioned as the result of operation of the actuating means, and means for releasably holding the freely mounted drum from movement until the spring is tensioned, whereby upon release of said freely mounted drum the spring functions to impart movement thereto.

14. Controlling mechanism for a knitting machine comprising, in combination, a bracket, a spindle rotatable in said bracket, a drum which presents a controlling formation and is fixedly mounted on said spindle, actuating means for rotating said drum positively step-by-step, another drum which presents a controlling formation and is freely mounted on said spindle, spring means which are associated with the freely mounted drum and adapted to be loaded by the actuating means, a toothed member which is attached to the freely mounted drum, a catch for co-operation with said toothed member to hold the freely mounted drum from movement whenever the spring means are being loaded by the actuating means, a part which carries said catch and is slidably mounted in the aforesaid bracket, and means for moving the catch out of engagement with the toothed member to release the freely mounted drum at predetermined times whereupon the spring means function to impart movement to the latter.

15. Controlling mechanism according to claim 14, wherein the catch is operated by a cam in timed relation with the operative movements of the actuating means.

16. Controlling mechanism according to claim 6, wherein the catch is operated in such a way that the spring operated part is racked one step after each step in the racking movement of the other controlling part.

17. Controlling mechanism for a knitting ma-

chine comprising, in combination, a bracket, a spindle rotatable in said bracket, a drum which presents a controlling formation and is fixedly mounted on said spindle, two juxtaposed coaxial ratchet wheels which are keyed on the spindle, said wheels having teeth of the same pitch and being oppositely arranged, a pair of spring-controlled clawers one for co-operation with each ratchet wheel, a bar upon which said clawers are mounted, means for reciprocating said bar to impart operative and idle strokes to the clawers, a movable bluff member formed with arcuate bluffing portions for controlling engagement of the clawers with the ratchet wheels, said wheels, clawers and associated parts together constituting means for enabling forward and reverse rotation to be imparted to the spindle according to requirements, another controlling drum which has formed thereon a radial lug and is freely mounted on said spindle, a pair of blocks mounted for movement slidably in one of the ratchet wheels, one on each side of said lug, a pair of pins one in each block at the end thereof opposing the lug, a tension spring which is engaged with said pins, a pair of screws one inserted in each block at the other end, a pair of plates attached to the last mentioned ratchet wheel, one plate opposing the screw in one block and the other plate opposing the screw in the other block, the arrangement being such that the spring is tensioned as the result of operation of the actuating means, a toothed member which is attached to the freely mounted drum, a catch for co-operation with said toothed member to hold the freely mounted drum from movement whenever the spring means are being loaded by the actuating means, a part which carries said catch and is slidably mounted in the aforesaid bracket, and means for moving the catch out of engagement with the toothed member to release the freely mounted drum at predetermined times whereupon the spring means function to impart movement to the latter.

18. Controlling mechanism for a knitting machine comprising, in combination, a part presenting a controlling formation, actuating means for operating said part positively, another part presenting a controlling formation, means associated with the second mentioned part and adapted to be influenced by said actuating means and, when required, to impart movement to said second mentioned part, and means for releasably holding the latter from movement until the first mentioned part has been operated by the actuating means, whereby upon release of the second mentioned part the aforesaid means influenced by the actuating means then function to impart movement to said second mentioned part.

ALFRED WOODWARD KENT. 60
HENRY HAROLD HOLMES.
